UNITED STATES PATENT OFFICE.

WILLIAM E. PERRINE, OF CLEVELAND, OHIO, ASSIGNOR OF ONE-THIRD TO CHRISTIAN GIRL, OF CLEVELAND, OHIO, AND ONE-THIRD TO ERNEST W. FARR, OF CLEVELAND HEIGHTS, OHIO.

DESIGN FOR A VEHICLE-WHEEL ANCHORAGE DEVICE.

42,090.

Specification for Design.

Patented Jan. 9, 1912.

Application filed October 3, 1911. Serial No. 652,660. Term of patent 14 years.

To all whom it may concern:

Be it known that I, WILLIAM E. PERRINE, a citizen of the United States, residing at Cleveland, in the county of Cuyahoga and State of Ohio, have invented a new, original, and ornamental Design for Vehicle-Wheel Anchorage Devices, of which the following is a specification, reference being had to the accompanying drawing, forming part thereof.

The figure is a perspective view of a vehicle wheel anchorage device, showing my new design.

I claim:

The ornamental design for a vehicle wheel anchorage device, as shown.

WM. E. PERRINE.

Witnesses:

J. B. HULL,
BRENNAN B. WEST.
